United States Patent

Des. 239,865
Patented May 11, 1976

239,865

RADIO

Jerome L. Pinsler, Evanston, and Anson Isaacson, Chicago, Ill., assignors to Marvin Glass & Associates, Chicago, Ill.

Filed Sept. 4, 1974, Ser. No. 502,921

Term of patent 14 years

Int. Cl. D14—03

U.S. Cl. D56—4 B

FIG. 1 is a perspective view of a radio showing our new design;

FIG. 2 is a view similar to FIG. 1 with the hood in raised position;

FIG. 3 is a top plan view of the radio with the hood in closed position;

FIG. 4 is a front elevational view thereof;

FIG. 5 is a right side elevational view, the left side being a mirror image thereof;

FIG. 6 is a rear elevational view; and

FIG. 7 is a bottom plan view.

We claim:

The ornamental design for a radio, as shown and described.
